UNITED STATES PATENT OFFICE.

DON COLE, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,384,429.

Specification of Letters Patent. Patented July 12, 1921.

Application filed February 11, 1918. Serial No. 216,439.

To all whom it may concern:

Be it known that I, DON COLE, a citizen of the United States, residing at Chicago, in the county of Cook and State of Illinois,

5 have invented a certain new and useful Improvement in Carbureters, of which the following is a full, clear, concise, and exact description, reference being had to the accompanying drawings, forming a part of

10 this specification.

My invention relates to carbureters.

The present condition of the art and the market demands an inexpensive carbureter for cars of relatively low power, capable of 15 providing a good working mixture throughout the range of operation with the fuel available at the present time. Economy of operation is a prime consideration.

It is the primary object of my invention 20 to provide a carbureter to meet the above requirements. I do not intend to limit the invention to such use only, as the principles set forth may be embodied in a great variety of forms.

25 It is well known that an internal combustion engine does not operate at top efficiency when operating at lower speeds. But in the practical operation of the automobile it is found that by far the greater part of the 30 mileage is traveled at relatively slow engine speeds.

I have observed an important fact with regard to the operation of the carbureter when the engine is running on slower speeds 35 and that is, that conditions within the engine manifold are more favorable for efficient vaporization or atomization of the fuel at lower speeds than at higher speeds. This condition is due to the action of the throttle.

40 When the throttle is closed or substantially closed, a condition of high suction prevails in the manifold, and the liquid fuel is more easily vaporized under the reduced pressure. Besides, the passage of the liquid fuel at high

45 speed under the lip of the throttle tends to tear up and atomize the liquid fuel more easily than when the throttle is further open. Due to this condition of better vaporization and atomization the mixture is

50 more even and more nearly homogeneous so that to secure the same explosive effect actually less fuel is required than would be required to form an equivalent mixture under different throttle and manifold conditions.

55 I take advantage of this fact by providing

means for thinning out the fuel proportions, when the throttle is in positions approaching the closed position.

I do this by providing a special bleeding chamber and passageway as will be described more in detail.

By thus reducing the quantity of fuel fed at low speeds, I am able to save a very considerable proportion of the fuel and to secure highly efficient and satisfactory opera- 65

70 The particular means which I employ to secure the economizing action, as I call it, is noteworthy as it secures not only the thinning out action desired but at the same time it incorporates the air which thins out the mixture in a finely subdivided state in the fuel fed to the nozzle, rendering the same more fluid and capable of easier movement and control.

75 The bleeding chamber is an enlarged section of the passageway between the float chamber and main nozzle, preferably lying in a vertical part of the passage. An atmospheric passageway, the inlet to which is controlled in accordance with the position of the throttle, opens into the chamber preferably at the side.

80 A small nozzle or tip projecting above the floor of the chamber communicates with the float chamber and supplies fuel for atomization in the chamber. The air entering from the bleeder passageway brushes over the tip, breaking up the liquid into a fine spray or mist, the fuel being broken up so that solid 90 liquid does not at any place fill the full cross section of the discharge passageway.

95 In furtherance of the main object, I aim by the present invention to provide an improved fuel nozzle and an economizer in operative relation thereto, an improved throttle and air bleed economizer, an improved air bleeder for the idling nozzle, an improved primer and an improvement in the general relation of the various parts of the carbureter as will be apparent from the following detailed description of a particular embodiment of my invention.

100 In the following drawings which form a part of the present specification,

105 Figure 1 is a top plan view of a specific embodiment such as is adapted for a popular light four-cylinder car;

110 Fig. 2 is a vertical longitudinal section of the same;

Fig. 3 is a section taken on the line 3—3 of Fig. 1;

Fig. 4 is a fragmentary section taken on the line 4—4 of Fig. 3; and

5 Fig. 5 is an enlarged detail section of the sensitive jet.

The body of the carburetor comprises a horizontal barrel 1 having an outlet 2. At the outlet end, the barrel or casing 1 is provided with an elbow 3 which opens upwardly at 4 to form the intake of the carburetor. Within the barrel 1 there is formed a carbureting chamber 5, and between this chamber and the outlet 2 there is provided 10 a throttle valve 6. The throttle valve 6 is mounted upon a vertical shaft 7, which shaft is adapted to be oscillated by the controlling lever 8 as will be described in detail later.

20 The elbow 3 is considerably enlarged to permit of free movement of the air without forming eddies. From the lower wall of the elbow, a post 9 projects upward bearing the hollow head 10 at its upper end. A 25 small Venturi tube 11 is inserted into the hollow head 10 and projects in line with the axis of the carbureting chamber 5, toward the outlet 2.

Within the main barrel 1, there is provided the main venturi 12 which co-operates with the secondary venturi 11. The venturi 11 has its inner end extending slightly beyond the most restricted portion of the main venturi 12. The main venturi 12 is 30 held in place by means of a set screw 13.

A constant level liquid fuel supply chamber 15 is formed integrally with the barrel 1. This chamber 15 is supplied with liquid fuel by way of the pipe connection 16, elbow 40 17 and passage 18. The passage 18 is controlled by a needle valve 19, which in turn is governed by a float 20 and suitable controlling mechanism 21.

Below the post 9, and in line therewith, 45 there is formed an extension or well casing 22 having a well 23 therein. This well 23 communicates with the float chamber 15 by way of the passage 24.

The venturi 11 has a shoulder 25 by 50 which it is adapted to be turned and screw threaded into the head 10. A peripheral groove 26 forming an annular passageway communicates by way of nozzles or ports 27 with the interior of the tube 11. This 55 annular passageway 26 communicates with the well 23 by way of a vertical passageway 28 which has a restriction 29 formed in the bushing or nozzle 30. The restricted passageway 29 is of considerably smaller size 60 than the passages 28 and 31 and the reduced end of the nozzle projects up into the intersection of the passages 28 and 31 as illustrated.

A transverse bleeder passageway 31 communicates with the passageway 28 above

the restriction 29. The passageway 31 is joined by a vertical passageway 32 which, at its upper end, is open to atmosphere at 34, as is also the float chamber by way of the opening 34'. It will be apparent that 70 the passageways 28, 31 and 32 form a U-shaped passageway. The passageway 32 is controlled by a valve 33, operating in connection with a valve seat 35 in the passageway 32. The stem 37 of the valve 33 is provided with a threaded portion 36 having coarse threads co-operating with a suitable threaded portion in the extension of the passage 32.

At its upper end the valve stem 37 is secured to a nut 38 which is screw-threaded and pinned to the stem. The lower surface 39 of the nut 38 is provided with corrugations which are adapted to engage similar corrugations upon the lever arm 40. The corrugations on the bottom of the nut 38 and on the upper surface of the lever 40 are held in engagement by the means of a spring 41, mounted upon the stem 37. The lever arm 40 is connected by a pair of links 42 to a crank arm 43 which is pinned (as is shown at 44) to the rock shaft 7 which controls the throttle valve 6. The crank arm 43 has a hub 45, having a stop arm 46 adapted to engage the plug 47 at one limit 95 of its movement and to engage the stop pin or screw 48 at the other limit of its movement.

The hub 45 also has a collar 49 extending out along the rock shaft 7 and the throttle lever 8 is clamped upon this sleeve 49 and thus connected to the shaft 7. The adjacent end of the throttle lever 8 is slotted as shown at 50 and is provided with a screw 51 for clamping the hub 49 in any desired position.

The hollow boss 10 is connected by lateral post 52 to the side walls of the casing. This post contains a passageway 53, communicating with the annular passageway 26 and leading to the idling nozzle 54. The passageway 53 is controlled by a needle valve 55 which is adjustable to vary the flow through the same. The passageway 53 communicates with a longitudinal passageway 56, which is drilled into the metal of the side walls and closed by a plug 57 at the outer end.

The idling nozzle 54 is formed by means of a threaded plug 58, screwed into a transverse opening intersecting the passageway 56. The front face of the plug 58 is slightly below the inner surface of the bore of the carburetor or mixing chamber to form a small by-pass 59 under the edge of the throttle valve 6.

In the lower part of the body 1 there is formed a passageway or opening 61 which communicates by way of the port 62 with a nozzle 63 formed in the body of the barrel in 130

front of the throttle valve 6. A spring plunger 65 constituting a valve for controlling the port 62 lies in an opening 64 between the ports 62 and the nozzle 63. The 5 outer end of this enlarged opening is closed by a bushing 66 in which the plunger 65 is adapted to slide. The passageway 62-63 passes under the end of the throttle shaft 7. As the valve 65 is normally closed this does 10 not interfere with the normal full feed. At its outer end, the plunger is provided with a coupling 67 by which it is adapted to be connected to a cable (or the like) connecting with a pull member for opening the valve. 15 The nozzle, 63 is so placed with respect to the outlet 2 that when the valve plunger 65 is moved to the open position the liquid fuel which emerges from the jet or nozzle 63 will be thrown into the manifold 68 shown in dotted line and swept into the engine to provide a rich mixture at starting.

The inlet 4 is controlled by a butterfly valve 69 pivoted on a rock shaft 70. This 25 rock shaft is provided with an operating arm 71 which is adapted to be connected by a suitable operating element such as a Bowden cable to an adjustable member on the dash or on the steering column of the 30 automobile. To this end a bracket 72 is attached to the side of the inlet in such a position as to grip the sheath of the Bowden cable. This bracket also serves as a stop member to be engaged by the downwardly 35 extending lug 71' on the operating arm 71. The inlet butterfly valve 69 is provided with an opening 73 to provide for a minimum of air to be admitted when the engine is started.

40 A drip opening 74 is provided in the bottom of the elbow 3.

The operation of the carburetor is as follows:

Assuming that the constant float chamber 45 is properly supplied with liquid fuel and it is desired to start the engine, the butterfly valve 69 may be closed to restrict the entry of air. The level of liquid fuel stands at a point approximately even with the top of 50 the passageway 28. The priming valve 65 is opened to discharge liquid fuel rather freely into the manifold 68 as the engine is turned over. This provides a starting supply from which enough volatile constituents 55 may be drawn for starting the engine.

When the engine is idling, the throttle 6 is closed and the idling nozzle 54 discharges under the edge of the throttle and the bypass 59 permits the passage of air around 60 the edge of the throttle at this point. The fuel is drawn from the nozzle 54 by way of the passages 56, valve 55, passageway 53, channel 26 and passageway 28, through the restriction 29 from the well 23 which is 65 in communication with the float chamber.

As the nozzles 27 open into the annular channel 26, air joins the gasoline by way of the nozzle 27, channel 26 and enters by way of the passage 53 and bleeds the idling nozzle 54, providing the proper mixture for 70 the engine when the same is just turning over. The amount of air drawn through the main body of the carburetor is so small at this time as not to have enough effect to draw any appreciable quantity of fuel at the 75 openings 27.

As the throttle 6 is slightly opened to permit more air to pass thereby, the air drawn through the main body of the carburetor so increases as to initiate the feed 80 at the nozzle at 27.

Due to the combined effect of the main venturi 12 and venturi 11, the suction upon the nozzles 27 arises upon the movement of relatively small quantities of air through 85 the body of the carburetor. As soon as suction is developed at that point, the air bleed by way of the port 34, valve 33 and passages 32 and 31 becomes effective. The interconnection between the throttle valve 90 6 and the bleeder controlling valve 33 is such that the bleeder valve has its maximum openings for the closed position of the throttle 6. The effect is to secure greater air bleed at closed than open throttle so that 95 the jet is compensated to secure a proper mixture for the various engine speeds.

As the throttle 6 is opened wider, the air bleed valve 33 is closed to a greater extent, consequently the suction has greater effect 100 upon the jet in drawing gasoline from the constant level chamber.

The relation between the throttle and the air bleeder valve may be adjusted by pressing down the end of the lever 40 which engages the nut 38 and turning the valve stem to the proper position, then releasing pressure on the lever 40. The spring 41 thereafter holds the nut 38 and the lever 40 in fixed relation. The nut 38 is pinned or 110 otherwise rigidly secured to the stem 37.

The bushing or nozzle 30 has a reduced nozzle part or tip 80 which projects up above the floor of the chamber 81 formed at the intersection of the horizontal air bleeder passageway 31 and the vertical discharge passageway 28. This arrangement is highly effective for breaking up the liquid fuel before it is drawn out of the nozzle openings 27, where atomization is completed. The air 120 entering the chamber 81 by way of the horizontal passageway 31 strikes the vertical stream of gasoline as it issues from the tip 80 and breaks it up. This arrangement provides a sensitive atomizer between the supply chamber and the point of discharge. I term it sensitive as a considerable variation in effect may be secured by varying the amount of air admitted for a given setting of the height of the tip and the size of the 130

chamber. Variations in the height of the tip 80 above the floor of the chamber also causes changes in effect of vaporization.

I claim:

- 5 1. In a carbureter, a carbureting chamber having an air inlet and a mixture outlet, a throttle in said mixture outlet, a constant level liquid fuel supply chamber, a passageway having means for the admission of air at one end and terminating at the other end in a fuel nozzle feeding to said carbureting chamber, a restricted connection between said constant level fuel supply chamber and said passageway, said restricted connection feeding into said passageway below the fuel level in said supply chamber, a valve controlling the air admission end of said passageway, and means mechanically connecting said throttle and said valve.
- 10 2. In a carbureter, a carbureting chamber having an air inlet and a mixture outlet, a throttle in said mixture outlet, a constant level liquid fuel supply chamber, a passageway having means for the admission of air at one end and terminating at the other end in a fuel nozzle feeding to said carbureting chamber, a restricted connection between said constant level fuel supply chamber and said passageway, said restricted connection feeding into said passageway below the fuel level in said supply chamber, a valve controlling the air admission end of said passageway, means mechanically connecting said throttle and said valve, and means for adjusting the relationship of said valve and said mechanical adjusting means.
- 15 3. In a carbureter, a carbureting chamber having an air inlet and a mixture outlet, a throttle in said mixture outlet, a constant level liquid fuel supply chamber, a U-shaped passageway having means for the admission of air to one leg thereof and having its other leg terminating in a fuel nozzle feeding into said carbureting chamber, a restricted connection between said constant level fuel supply chamber and said U-shaped passageway, said restricted connection feeding into said

U-shaped passageway near the bottom of the U and below the fuel level in said supply chamber, a valve controlling the air admission end of said passageway, and means mechanically connecting said throttle and said valve, whereby opening movement is imparted to said valve by closing movement of the throttle, and vice versa.

4. In a carbureter, a carbureting chamber having an air inlet and a mixture outlet, a throttle in said mixture outlet, a constant level liquid fuel supply chamber, a passageway having means for the admission of air at one end and terminating at the other end in a fuel nozzle feeding to said carbureting chamber, a restricted connection between said constant level fuel supply chamber and said passageway, said restricted connection feeding into said passageway below the fuel level in said supply chamber, a valve controlling the air admission end of said passageway, means mechanically connecting said throttle and said valve, and means for adjusting the relationship of said valve and said mechanical adjusting means.

5. In a carbureter, a carbureting chamber having an air inlet and a mixture outlet, a throttle in said mixture outlet, a constant level liquid fuel supply chamber, a passageway having means for the admission of air at one end and terminating at the other end in a fuel nozzle feeding to said carbureting chamber, a restricted connection between said constant level fuel supply chamber and said passageway, said restricted connection feeding into said passageway below the fuel level in said supply chamber and during operation with air passing through said passageway, a valve controlling the air admission end of said passageway, and means mechanically connecting said throttle and said valve whereby opening movement is imparted to said valve by closing movement of the throttle, and vice versa.

In witness whereof, I hereunto subscribe my name this 7th day of February, A. D. 1918.

DON COLE.
